UNITED STATES PATENT OFFICE.

FREDERICK ROETTGES, OF NEW YORK, N. Y., ASSIGNOR TO HARRY HILFMAN, OF NEW YORK, N. Y.

DESIGN FOR A CHANDELIER OR THE LIKE.

Application filed October 3, 1925. Serial No. 14,999. Term of patent 3½ years.

To all whom it may concern:

Be it known that I, FREDERICK ROETTGES, a citizen of the Republic of Germany, residing in the city, county, and State of New York, have invented a new, original, and ornamental Design for a Chandelier or the like, as shown, of which the following is a specification, reference being had to the accompanying drawing, forming part thereof.

The figure is a side view partly in perspective of a chandelier showing my design.

I claim:—

The ornamental design for a chandelier or the like as shown.

FREDERICK ROETTGES.
